UNITED STATES PATENT OFFICE.

JESSE B. McAFFEE, OF DALLAS, TEXAS.

DESIGN FOR A PHYSICIAN'S TRAFFIC-SIGNAL.

58,097.

Specification for Design.

Patented June 7, 1921.

Application filed January 3, 1921. Serial No. 434,819. Term of patent 3½ years.

To all whom it may concern:

Be it known that I, JESSE B. McAFFEE, a citizen of the United States, residing at Dallas, in the county of Dallas and State of Texas, have invented a new, original, and ornamental Design for a Physician's Traffic-Signal, of which the following is a specification, reference being had to the accompanying drawing, forming part thereof.

Figure 1 is a face view of a physician's

traffic signal showing my new design. Fig. 2 is an edge view of the same, the cross being lined to indicate green, but is designed to represent any color with the exception of red.

I claim:

The ornamental design for a physician's traffic signal as shown.

JESSE B. McAFFEE.
